UNITED STATES PATENT OFFICE.

CLEMENT F. STREET, OF GREENWICH, CONNECTICUT.

ADJUSTABLE FUEL DISTRIBUTOR.

Application filed December 19, 1923. Serial No. 681,550.

To all whom it may concern:

Be it known that I, CLEMENT F. STREET, of Greenwich, in the county of Fairfield and State of Connecticut, have invented certain new and useful Improvements in Adjustable Fuel Distributors, of which the following is a specification.

This invention relates to fuel distributors for use particularly in connection with locomotive stokers, the principal object being to provide an improved form of distributor and means for adjusting the same, whereby the fuel may be distributed upon any particular portion of the grate area as may be desired.

In the accompanying drawings: Figure 1 is a vertical central section of an adjustable fuel distributor embodying my improvement; Fig. 2, an end elevation; Fig. 3, a transverse section taken on the line 3—3 of Fig. 1; Fig. 4, a plan; Fig. 5, a transverse section taken on the line 5—5 of Fig. 4; Fig. 6, a perspective view of the end portion of the lower half of the distributor; and, Fig. 7, a horizontal section taken on the line 7—7 of Fig. 5.

According to the usual practice of mounting a fuel distributor in a locomotive boiler, an opening is made through the back head, 30 and a tube, 9, is inserted through the water space to connect the two boiler sheets to which it is welded to form a water tight joint. The distributor is then inserted through the tube, 9, and communicates at its 35 rear end with an elbow, 12, to which is connected a pipe or conduit, 13, which serves to deliver the fuel from a source of supply to the distributor, the fuel being driven by steam or compressed air from a jet nozzle, 40 connected to supply pipe, 24, and controlled by a valve, 25.

It has also been proposed to provide a distributor with means for partially rotating or rocking the same within the tube for the purpose of adjusting the position of the entire distributor upon its axis in order to deliver fuel to different portions of the fire box, but this does not operate to reach all parts of the grate. According to my improvement the distributor is formed in separate sections, which are independently adjustable, whereby various combinations of the deflecting surfaces may be obtained for producing a wider range of distribution.

According to the construction shown, the

distributor is made in two sections, an upper section, 10, and a lower section, 11. The lower section, 11, rests on the tube, 9, in which it is adapted to be partially rotated when adjusted to different positions. The 60 upper section, 10, is mounted on the top of the lower section, 11, on which it is adapted to be rocked, or partially rotated, during manual adjustment. The forward end of the lower section, 11, projecting within the 65 firebox, is provided with two curved ribs, 11^a, designed for the purpose of distributing the fuel to the back corners of the grate, while the forward projection of the upper section, 10, is provided with a fan-shaped 70 series of corrugations, 10^a, diverging toward the forward end, for scattering the coal over the forward section of the firebox, and along the side sheets. The upper and lower sections, 10 and 11, are connected at their rear 75 ends, to the elbow, 12, by means of shoudered cap screws, 18, extending through slots formed in the lugs, 12^a, on the elbow, the slots allowing for the partial rotary, or 80 rocking motion which may be given to either 85 one or both of said sections, when manually adjusted for distributing the coal upon different portions of the grate.

Any suitable means may be employed for rocking the distributor sections, but I have 85 shown a stud, 14, link, 15, and lever, 16, for the lower section, and an adjusting handle, 20, connected directly to the upper section. The lower section may be clamped by a locking nut handle, 17, which is mounted on the 90 fulcrum bolt of lever, 16, after being set in any desired position, and the upper section, 10, may be locked by means of the clamping nut, 23, on bolt, 22, mounted on the elbow, 12, and extending through a curved slot, 21, 95 in the arm of the handle, 20.

In the operation of this device, the coal is delivered to elbow, 12, through the conduit, 13, and driven from elbow, 12, into the firebox through the distributors by a jet of 100 steam or air which enters through the pipe, 24, the flow being controlled by globe valve 25. After the coal passes through the opening between the two distributors, a portion of it comes in contact with the curved ribs, 11^a, and is diverted from its natural course to a point one side or the other of the distributor. That portion of the coal which passes over the ribs, 11^a, comes in contact with an inclined surface, 11^b, which forms a 110

- part of this distributor, which inclined surface drives the coal upward against the upper half of the distributor. This upward movement brings the coal in contact with the corrugations, 10^a, and has a tendency to give it a definite and well-defined line of direction as it passes into the firebox, which line of direction can be controlled by the form and angle of the corrugations.
- 10 The primary object of this design of distributor is to enable the operator to make changes in the proportion of coal which is delivered to the different parts or zones of the firebox. Under normal conditions, both 15 the top and the bottom distributors would be practically horizontal and while in this position are designed so as to give a fairly uniform distribution of the coal throughout the entire grate surface. Should it be desired to place an additional amount of coal in the lower right hand corner, the operating lever, 16, of the lower distributor would be thrown to the right. This motion of the distributor will throw the central point, 20 25 11°, of the ribs, 11^a, to the left side of the center of the stream of coal which is entering the firebox, and at the same time will drop the right hand side of the distributor, increasing the inclination of the surface (which is already inclined in the form of the casting) and causing the coal to fall down into the right hand corner.
- Should it be desired to increase the quantity of coal going to the left hand corner of the fire box, the lever 16 is thrown to the left, and the result is just the reverse of throwing it to the right.
- Should it be desired to put a heavy fire in both back corners, by throwing the lever, 40 45 16, first to the extreme right and then to the extreme left, a heavy bank can be piled in either back corner.
- The operation of the upper distributor section for covering the center and forward portions of the firebox is just the same as the operation of the lower section, except the movement is reversed. If it is desired to fire heavy on the right hand front section of the firebox, the lever, 20, is thrown 50 to the left, and if it is desired to fire heavy

on the left hand side, the lever, 20, is thrown to the right.

If it is desired to fire heavy on the back right hand corner and the front left hand corner of the grate, both levers, 20 and 16, 55 are thrown to the right. It will thus be seen that by movement of these levers any of the four zones or sections of the grate can be fired heavy as desired.

As there are many forms of distributors, 60 both movable and fixed, it is understood that my invention is not limited to any particular form, and it may also apply where there are a plurality of distributors for the firebox.

Having now described my invention, what 65 I claim as new and desire to secure by Letters Patent is:

1. A fuel distributor formed in two sections, an upper and a lower, the lower section being adapted to be mounted in a furnace wall, and the upper section mounted on the lower section with the capacity of a partial rotary movement thereon, and means for rotatably adjusting the upper section relative to the lower. 70

2. A fuel distributor formed in two sections, an upper and a lower, the lower section being adapted to be mounted in a furnace wall, and the upper section mounted on the lower section with the capacity of a 80 partial rotary movement thereon, and means for rotatably adjusting either section relative to the other.

3. A fuel distributor formed in two sections, an upper and a lower, mounted for 85 independent rotary movement, the upper section having a forward projection with diverging corrugations, and the lower section having curved ribs and an upwardly inclined surface, and means for rotatably 90 adjusting said sections independently.

4. As an article of manufacture, a distributor divided longitudinally into sections, 95 said sections being capable of partial rotation about the longitudinal axis of the distributor independently of each other.

In testimony whereof I have hereunto set my hand.

CLEMENT F. STREET.
